LOCK

Charles B. Lowe, Stamford, Conn., assignor to
The Yale & Towne Manufacturing Company,
Stamford, Conn.

Application July 6, 1931, Serial No. 548,770

19 Claims. (Cl. 70—46)

This invention relates to cylinder locks of the type adapted to be mounted within a housing and retained within that housing for predetermined operation. More particularly, the invention relates to a cylinder lock containing a key plug and bolt mechanism controlled by key operation of the key plug, whereby the cylinder may be released for predetermined movement within a housing for the purpose of controlling predetermined mechanism, such as an electric switch, a steering wheel, or other device.

More in detail, my invention comprises a cylinder mounted for sliding movement within a housing and normally locked against such sliding movement by a bolt. This bolt is actuated by rotation of the key plug of the cylinder so as to release the cylinder for sliding movement, during which sliding movement it controls certain mechanism in a manner well understood in this art. An important feature of my invention is the means for controlling the movement of the cylinder within the housing while permitting its ready removal from the housing. A further important feature of the invention resides in the means for retaining the plug within the cylinder, and in the mounting of the key plug controlling bolt.

Before describing the detailed construction of a particular modification of my invention, it will be helpful to review generally its constructional features and thus point out the contributions which I have made to the art. My cylinder lock contains a key plug which is inserted into the cylinder and thereafter is retained in the cylinder by a member which, preferably, is in the form of a blocking member. This blocking member prevents removal of the plug from the cylinder and, preferably, is itself retained in the cylinder by a bolt protruding beyond the periphery of the cylinder so as to cooperate with a retaining slot in the housing in which the cylinder operates. It therefore serves not only to retain the blocking member and key plug within the cylinder, but also coacts with the housing to retain the cylinder in the housing and to limit the movement of the cylinder in the housing. As a further feature, the blocking member preferably houses a bolt which is adapted to do the actual locking of the cylinder within the housing, and which bolt is actuated by the key plug.

For a more detailed description of my invention, I shall refer to the drawing wherein Fig. 1 is a plan view of my invention, while Fig. 2 is a front end view of the same. Fig. 3 is a rear end view of the housing, showing its open end.

Fig. 4 is a section of the housing, showing the cylinder lock in a released position, while Fig. 5 illustrates the position of the key in the same in that unlocked position. Fig. 6 shows means for removing the cylinder from the housing and Fig. 7 is a view similar to Fig. 5. Fig. 8 is a section of the cylinder showing the locking plug and the retaining means and the locking bolt in position. Fig. 9 is a front end view of the cylinder, while Fig. 10 is a plan view of the same, showing its outward appearance. Fig. 11 is a section along the lines 11—11 of Fig. 8. Fig. 12 is a section along the lines 12—12 of Fig. 8, while Fig. 13 is a section along the lines 13—13 of Fig. 8. Fig. 14 is a view similar to Fig. 8 showing the retaining backing means for the plug in plan rather than by sectional view. Fig. 15 is a rear view of Fig. 14.

Referring now more particularly to the drawing, reference numeral 10 indicates a cylinder housing adapted to house a cylinder 11 containing a locking plug 12 operable by a key 13. The plug 12, when operated by the key 13 in the usual manner understood in this art, is adapted through its pin 23 to retract a locking bolt 14 which cooperates with a slot 15 in the cylinder housing 10, so as to release the cylinder for movement from the position of Fig. 1 to the position illustrated in Fig. 4. In this position, a spring pressed retaining bolt 16 will cooperate with the slot 15 to retain the cylinder in its position illustrated in Fig. 4.

A spring 17 is present to urge the cylinder 11 from its position of Fig. 1 to its position of Fig. 4 whenever the cylinder is released by movement of the locking bolt as just described. It will be readily understood that movement of the cylinder from the locking position of Fig. 1 to the unlocked position of Fig. 4 will release certain mechanism which it controls as will be clear to those skilled in the art.

When it is desired to remove the cylinder from its housing, a tool 18 may be used to depress the retaining bolt 16 as illustrated in Fig. 6 so that the cylinder may be readily removed as will be quite clear.

Referring now more particularly to Figs. 8 to 15 inclusive, my key plug 12 is illustrated as containing a plurality of tumblers 19 whereby it is locked against rotary movement in the cylinder 11, insertion of the key being adapted to release the plug and permit its rotation in the usual way. This plug 12 has a head 20 which is smaller in diameter than the body of the plug, and forms a shoulder 20 therewith, so that the plug may be

inserted rearwardly into the cylinder into its position of Fig. 8 where the shoulder will maintain the plug against further outward movement.

In order to maintain the plug in the cylinder against movement opposite to its direction of insertion, the backing member 21 shown in Fig. 14 is used, this member being cut out at 22 for the bolt operating pin 23 of the plug 12, so that the main body of this backing member will abut the end of the plug and will maintain the plug in its position illustrated in Fig. 8. This backing member is further cut out for the retention of the locking bolt 14 and the retaining bolt or detent 16, the retaining bolt 16 being spring pressed in an outward direction by its spring 16'.

As will be readily understood, the detent retaining bolt 16 will cooperate with the opening 24 in the cylinder through which it protrudes to maintain the backing member and consequently the plug within the cylinder 11. At the same time, it cooperates with the backing member and the outer shell to maintain the cylinder 11 within the housing 10, and for limiting the movement of the cylinder relatively to that housing when released by key operation. As will be noted especially in Fig. 10, the opening 25 through which the locking bolt 14 extends outwardly from the cylinder into the locking slot 15, is slightly enlarged so that the bolt 14 will slide freely relatively to the cylinder. This not only contributes a non-frictional sliding action of the bolt, but puts all the retaining stress on the auxiliary bolt detent 16.

While I have shown a particular modification of my invention, it should be understood that variations of the same within the scope of the appended claims will readily occur to those skilled in the art.

I claim:

40 1. In a lock, a housing, a cylinder mounted for movement in said housing, a key plug in said cylinder operable to control the movement of said cylinder in the housing, and a single means carried by the cylinder and adapted to retain the plug in said cylinder while simultaneously retaining said cylinder in the housing.

50 2. In a lock, a housing, a cylinder mounted for movement in said housing, a key plug in said cylinder operable to control the movement of said cylinder in the housing, and a single means adapted to retain the plug in said cylinder and said cylinder in the housing.

55 3. In a lock, a housing, a cylinder mounted for movement in said housing, a key plug in said cylinder operable to control the movement of said cylinder in the housing, a retaining bolt mounted in said cylinder and cooperable with the housing to retain the cylinder in said housing, and means whereby said retaining bolt retains the plug in said cylinder.

60 4. In a lock, a housing, a cylinder mounted for movement in said housing, a key plug and a plug operated bolt carried by said cylinder, means whereby said bolt cooperates with the housing to lock the cylinder against movement relatively thereto, a detent carried by the cylinder and cooperable with the housing to retain the cylinder in said housing, and means whereby said detent also retains the plug within the cylinder.

70 5. In a lock, a housing, a cylinder mounted for movement in said housing, a key plug in said cylinder, a backing member in said cylinder for retaining the plug in the cylinder, a pair of bolts mounted in said backing member, one of said bolts being adapted to lock said cylinder in said

housing, means whereby the said bolt is operated by said plug to lock and unlock the cylinder for movement in the housing, the other of said bolts being cooperable with the housing to retain the cylinder therein, and with the backing member to retain the plug in the cylinder.

5 6. In a lock, a cylinder, a key plug insertable endwise into said cylinder, means contained within the periphery of said cylinder adapted to abut said plug and obstruct its removal opposite to its direction of insertion, and a spring pressed detent cooperable with said means and adapted to maintain said means in the cylinder.

10 7. In a lock, a cylinder, a key plug insertable endwise into said cylinder, a backing member insertable endwise after said plug and adapted to maintain the plug in the cylinder, and a spring pressed detent mounted in said backing member and cooperable with the cylinder to maintain the backing member in the cylinder.

15 8. In a lock, a cylinder, a key plug insertable endwise into said cylinder, means in said cylinder adapted to obstruct removal of the plug, a detent in said cylinder for maintaining said obstructing means in operative position, a housing in which said cylinder is adapted to slide, said detent being cooperable also with the housing to retain and limit the movement of the cylinder within said housing.

20 9. The combination of claim 6, a housing in which said cylinder is adapted to slide, said detent being cooperable also with the housing to retain and limit the movement of the cylinder within said housing.

25 10. The combination of claim 7, a housing in which said cylinder is adapted to slide, said detent being cooperable also with the housing to retain and limit the movement of the cylinder within said housing.

30 11. In a lock, a cylinder, a key plug insertable endwise into said cylinder, a locking bolt mounted in said cylinder and operable by said key plug, means in said cylinder adapted to obstruct removal of the plug, and a detent in said cylinder for maintaining said obstructing means in obstructing position.

35 12. In a lock, a cylinder, a key plug insertable endwise into said cylinder, a locking bolt mounted in said cylinder and operable by said key plug, means in said cylinder to abut said plug and obstruct its removal opposite to its direction of insertion, and a spring pressed detent cooperable with said means and adapted to maintain said means in the cylinder.

40 13. In a lock, a cylinder, a key plug insertable endwise into said cylinder, a backing member insertable behind said plug and adapted to obstruct its removal from the cylinder, a locking bolt mounted in said backing member and operable by the key plug, and a spring pressed detent mounted in said backing member and cooperable with the cylinder to maintain the backing member in the cylinder.

45 14. The combination of claim 11, a housing in which said cylinder slides and with which the locking bolt cooperates to lock the cylinder against movement, said detent being cooperable also with said housing to retain and limit the movement of the cylinder relatively thereto.

50 15. The combination of claim 12, a housing in which said cylinder slides and with which the locking bolt cooperates to lock the cylinder against movement, said detent being cooperable also with said housing to retain and limit the movement of the cylinder relatively thereto.

16. The combination of claim 13, a housing in which said cylinder slides and with which the locking bolt cooperates to lock the cylinder against movement, said detent being cooperable also with said housing, to retain and limit the movement of the cylinder relatively thereto.

17. In a lock, a cylinder, a key plug insertable endwise into said cylinder, means in said cylinder adapted to obstruct removal of the plug, a 5 detent in said cylinder for maintaining said obstructing means in operative position, a housing in which said cylinder is mounted, and means

whereby said detent is cooperable also with the housing to retain the cylinder within said housing.

18. The combination of claim 6, a housing in which said cylinder is mounted, said detent being cooperable also with the housing to retain the cylinder within said housing. 5

19. The combination of claim 7, a housing in which said cylinder is mounted, said detent being cooperable also with the housing to retain the 10 cylinder within said housing.

CHARLES B. LOWE.
